United States Patent Office

Des. 191,016
Patented Aug. 1, 1961

191,016

SLIDE VIEWER

Warren G. Thomas, 205 Longfellow Ave.,
Toms River, N.J.

Filed Sept. 2, 1960, Ser. No. 61,992

Term of patent 3½ years

(Cl. D61—1)

FIG. 1 is a front perspective view of a slide viewer in a closed position and showing my new design;

FIG. 2 is a rear perspective view thereof;

FIG. 3 is a front perspective view thereof in an open position; and

FIG. 4 is an end view thereof in closed position.

The essential features of my design are shown in full lines.

I claim:

The ornamental design for a slide viewer, as shown and described.
